PUMP

Max O. Schreiter, Peoria, Ill.

Application May 6, 1943, Serial No. 485,909

7 Claims. (Cl. 103—5)

My invention relates to pumps, and has among its objects and advantages the provision of an improved pump designed to develop power which may be utilized for operating liquid engines and the like, in addition to serving as a general purpose pump.

In the accompanying drawings:

Figure 1 is a vertical sectional view of the pump.

Figure 2 is a horizontal sectional view.

Figure 3 is a vertical sectional view illustrating a pump plunger actuating means.

Figure 4 is a vertical sectional view illustrating a cam driving means.

Figure 5 is a sectional view of a gear pump and pressure relief valve, and

Figure 6 is a detail view of the gear pump.

In the embodiment of the invention selected for illustration, I make use of a pump body or housing 10 which is bolted at 12 to a base 14. This base may be secured to any suitable mount. A cover 16 is detachably connected with the body 10 by bolts 18. A vertical dividing partition or wall 20 is formed integrally with the side wall structure of the body 10. A shaft 22 is rotatably mounted in bearings 24 bolted at 26 to the wall 20 and one wall 28 of the body 10. The shaft 22 is provided with a crank 30 and has its end 32 rotatably supported in a bearing 34 attached to the side wall 36 of the body 10. Caps 38 are bolted at 40 to the walls 20 and 28 and are provided with stuffing boxes 42 which function as seals to prevent leakage of oil or other liquid to be pumped.

Both walls 20 and 28 are provided with relatively large openings 44 to accommodate the bearings 24.

To the wall 36 is attached a boss 46 having a cavity 48 in which are housed meshing pump gears 50 and 52. The gear 52 is keyed to a shaft 54, rotatably supported in a bearing 56 in the wall 36, the inner end of the shaft being provided with a small pinion 58 meshing with a larger pinion 60 keyed to the shaft end 32 for driving the shaft 54.

A tube 62 leading from a liquid source (not shown) has communication with the cavity 48, which cavity has communication with an outlet opening 64 extending through the wall 36. The chamber 66 in the body 10 is maintained full of oil or other liquid employed in the power pumping system.

In Figure 5, the boss 46 is provided with a port 68 having communication with a passage 70 in a cover 72 bolted at 74 to the boss and to

which the supply line 62 is attached by a coupling unit 76. The passage 70 has communication with the cavity 48. A compression spring 78 yieldingly holds a pressure relief valve 80 against a valve seat 82 about the port 68, which valve is normally seated but is lifted off its seat when the chamber 66 is completely filled with liquid so as to relieve the chamber from excessive pressure. A screw plug 84 is threaded into the bore 86

10 which houses the spring 78 to constitute an abutment for the spring, and the spring tension may be changed through adjustment of the plug. The wall 20 is so spaced with respect to the walls 28 and 36 as to provide a second chamber 15 88, in addition to the chamber 66. A connecting rod 90 is pivotally connected at one end with the crank pin 92 of the crank 30 and is arranged upright in the chamber 88. This rod is slidably mounted in a bore 94 in a rocker body 96. This 20 rocker body is provided with coaxial shafts 98 rotatably supported in bearings 100 attached to the walls 20 and 28. Thus actuation of the rod 90 through rotation of the crank 30 imparts an oscillatory motion to the body 96.

25 In Figure 3, the body 96 is provided with ears 102 pivotally connected at 104 with links 106. The links 106 are located on opposite sides of the body 96 and are respectively pivotally connected at 108 with pump plungers 110 slidably in bores 30 112 in bosses 114 on the side walls 116 of the body 10. Caps 118 are bolted at 120 to the bosses 114, which caps are provided with recesses or chambers 122 having communication with the respective bores 112. Bodies 124 are fixed to the 35 respective caps 118 and are provided with chambers 126 having communication with outlet tubes 128 leading to the engine (not shown) to be operated or to other types of machinery. The liquid or oil is discharged forcibly through the 40 tubes 128 through reciprocation of the plungers 110.

Figure 2 illustrates the chambers 126 as being provided with screw plugs 130 of tubular formation and provided with ports 132 which place 45 the bores 134 of the plugs in communication with the chambers 122. Valve bodies 136 are yieldingly biased against the wall faces of the respective ports 132 by compression springs 138 interposed between the valve bodies and plugs 140 50 threaded into the plugs 130. The bodies 136 are unseated in response to predetermined liquid pressures in the chambers 122. Such unseating takes place upon the pumping strokes of their respective plungers 110, and the bodies seat immediately as the plungers start on their retrac-

tion stroke. Communication between the chambers 122 and the chamber 66 is established by bores 142 in the bosses 114. These bores terminate in chambers 144 provided with seats 146 to be engaged by valves 148. The chambers 144 are placed in communication with the chambers 122 when the valves 148 are lifted off the seats 146. Both valves 148 are provided with stems 150 slidably guided in bores 152 in the bosses 114. Inside the chamber 66 the stems 150 are guided by brackets 154 bolted at 156 to the wall 20. Compression springs 158 are interposed between the body 10 and flanges or washers 160 keyed against axial movement on the stems 150. Thus the valves 148 are yieldingly biased to closed positions.

Heads 162 are attached to the stems 150 and engage a rotary cam 164 fixed to a shaft 166, see Figure 1, having shaft ends 168 rotatably supported in bearings 170 on the walls 20 and 36. A sprocket 172 is fixed to the shaft 166 and is driven by a chain 174 passing around a sprocket 176 fixed to the shaft end 32. A pulley 178 is fixed to the shaft 22 for connection with a driving belt (not shown). Rotation of the shaft 22 actuates the pump gears 50 and 52 of Figure 6, the cam 164 and the body 96.

The cam 164 is so arranged as to maintain the valves 148 in their closed positions during the power strokes of the plungers 110. The cam opens the valves upon the retraction of the strokes of the plungers 110 to create suction conditions in the chambers 122 and 148 and the bores 142, to fill these cavities, so that the chambers 122 as well as available space in the bores 112 will be filled with oil or other liquid to be forced from the chambers 122 and into the outlet tube 128 upon the power strokes of the plungers 110. One plunger 110 is under retraction as the other plunger is in its power phase. The plugs 130 are provided with openings 180 to pass liquid from the plugs into the chambers 126 for delivery to the outlet tubes 128.

The capacity of the pump gears 50 and 52 is such as to maintain the chamber 66 full at all times. The plungers 110 are arranged coaxially and are powerful, since the body 96 is located at some distance from the crank pin 92 so that a powerful leverage is imparted to the two plungers 110 through oscillation of the body 96.

The chamber 88 is also filled with oil. This chamber is effectively sealed by reason of the stuffing boxes 42. Since the chamber 88 is always full, the oil therein constitutes a backing or seal which prevents oil from leaking past the plungers 110 in the event of excessive wear thereon.

Without further elaboration, the foregoing will so fully explain my invention, that others may, by applying current knowledge, readily adapt the same for use under various conditions of service.

I claim:

1. A pump of the type described comprising a liquid supply chamber, a feed pump for maintaining a liquid supply in said chamber, a drive shaft having an operating connection with said pump, outlet tubes, pressure chambers having

communication with said outlet tubes and said chamber, reciprocating plungers for forcing liquid from said pressure chambers through the respective outlet tubes, valves controlling the flow of liquids from said chamber to said pressure supply chambers, an operating connection between said valves and said drive shaft for actuating the valves in timed relation with said plungers, and a rocker means operatively connecting said plungers and said drive shaft to reciprocate the plungers through rotation of the drive shaft.

2. The invention described in claim 1 wherein said rocker means includes a rocker body having a link connection with each of the plungers, a crank in said drive shaft, and a rod connected with said crank and slidably connected with said rocker body.

3. The invention described in claim 1 wherein said operating connection comprises slidable stems on said valves and a rotary cam for actuating said stems and operatively connected with said drive shaft.

4. The invention described in claim 1 wherein said pressure chambers are provided with valves biased to closed positions and opening only in response to predetermined liquid pressures for passing liquid to said outlet tubes.

5. A pump of the type described comprising a body having first and second chambers, a rotary shaft having portions thereof lying in said first and second chambers, a liquid pump communicating with the first chamber for maintaining a liquid supply therein, pressure chambers having communication with said first chamber an operating connection between said liquid pump and said shaft, said shaft having a crank located in said second chamber, a rocker body mounted in said second chamber and operatively connected with said crank to be rocked through rotation of the crank, liquid outlet tubes having communication with said pressure chambers, reciprocating plunger means operatively connected with said rocker body for forcing liquid through said outlet tubes, and valves operatively connected with said shaft for opening and closing communication between said first chamber and said pressure chambers in predetermined timed relationship with the reciprocatory motion of said plunger.

6. The invention described in claim 5 wherein said body is in the nature of a housing provided with a partition dividing the housing into said first and second chambers, and detachable bearings respectively attached to said partition and one wall of the housing to rotatably support said shaft.

7. The invention described in claim 5 wherein said body is in the nature of a housing provided with a partition dividing the housing into said first and second chambers, detachable bearings respectively attached to said partition and one wall of the housing to rotatably support said shaft, and stuffing boxes associated with said bearings.

MAX O. SCHREITER.
